(57) **ABSTRACT**

In one aspect of the present invention, a toy arrangement involving a flickering, animated and/or luminescent toy object will be described. The toy arrangement includes a toy object having a light sensitive layer. A light source is arranged to illuminate the light sensitive layer with a pattern revealing light. The light sensitive layer is arranged to emit colored light in response to exposure to the pattern revealing light. In some implementations, the light source is arranged to vary the intensity of the pattern revealing light, which in turn can cause the colored light emitted from the toy object to fade, brighten and flicker. The toy arrangement may also include a speaker that emits sounds that are synchronized with changes in the colored light.

COLOR CHANGING TOYS, GAMES AND DEVICES

CROSS-REFERENCE TO RELATED APPLICATION(S)

This application is a Continuation-in-Part of U.S. patent application Ser. No. 13/220,538 filed Aug. 29, 2011, which claims priority to U.S. Provisional Patent Application No. 61/378,335 filed Aug. 30, 2010. Each of these priority applications is incorporated herein by reference in their entirety for all purposes.

FIELD OF THE INVENTION

The present invention relates to the use of lighting in various toys, games and educational devices. Various embodiments of the present invention relate to the use of light to create animated sequences and visual effects to entertain and educate children.

BACKGROUND OF THE INVENTION

There are various toys and games on the market that generate a color change or glow. Some toys change color upon contact with water (e.g., U.S. Pat. No. 6,416,853 describes a diaper of a baby doll that turns yellow when exposed to water.) Another type of toy changes color when exposed to heat or cold (e.g., U.S. Pat. No. 5,716,253 involves a toy frying pan with bacon and eggs that changes color when placed over ice.) Other types of toys and games change color when physically deformed, such as a ball that can be squeezed to reveal the color of its inner core. (e.g., see U.S. Pat. No. 6,905,431.) Still another type of toy changes color using magnetic particles, as discussed in U.S. Pat. No. 7,607,919.

Although the above toys and games work well for various applications, there are ongoing efforts to make toys and games more educational and engaging for children.

SUMMARY OF THE INVENTION

In one aspect of the present invention, a toy arrangement involving a flickering, animated and/or luminescent toy object will be described. The toy arrangement includes a toy object having a light sensitive layer. A light source is arranged to illuminate the light sensitive layer with a light that is capable of revealing a hidden or invisible pattern. In various embodiments, the light sensitive layer is (nearly) invisible and the pattern revealing light emitted by the light source is (nearly) invisible to the human eye. The light sensitive layer is arranged such that atoms of the light sensitive layer become excited when exposed to the pattern revealing light. This causes the light sensitive layer to release energy in the form of a visible colored light in response to the emitted light.

In another aspect of the present invention, a method of illuminating a surface of an object to create animated effects will be described. An object (e.g., a toy, a doll, an action figure, a card, etc.) is provided that includes a light sensitive layer on its surface. The light sensitive layer may be generally invisible in the absence of a pattern revealing light. The light sensitive layer is then illuminated with the pattern revealing light from a light source. In various implementations, the light sensitive layer absorbs the pattern revealing light and emits a colored light in response. The intensity of the pattern revealing light is increased and decreased repeatedly. This causes the intensity of the emitted colored light to also increase and decrease (e.g., flash, flicker, fade, brighten, etc.), which in

some embodiments can create an appearance of physical motion on the surface of the object. A sound is generated at a speaker that is synchronized with the changes in the intensity of the emitted colored light. For example, when the colored light becomes brighter, darker or flickers, the volume of the sound may correspondingly increase, decrease or become intermittent. Different sounds may be played to match changes in the colored light.

This method may be applied to a wide variety of toys, 10 structures, games and game accessories. Various applications involve revealing a secret marking, making a simple cartoon, creating a light show or rewarding an action taken by a user with an animated sequence. In some embodiments, a feature 15 on a toy (e.g., a headlight on a toy car, a highlight in a doll's hair, a marking on a doll's clothing, a pattern on a game card, a mouth region on a face, etc.) bursts into color when appropriately illuminated with the pattern revealing light but is dim and/or invisible in its absence.

Through the use of color mixing and multiple light sources 20 and/or layers, a wide variety of light displays can be provided. By way of example, a surface of a toy may be covered by multiple light sensitive layers that each generate a different colored light. The colored light may be mixed with a colored light from a visible light source to increase the range of colors 25 that can be created. A visible, colored light and a pattern revealing light can be flashed rapidly in an alternating sequence, which generates a dynamic, multi-colored light show on the surface of the toy.

Another aspect of the present invention relates to various 30 toy arrangements that can make use of the above method. A particular implementation involves a toy arrangement that includes a tablet device and a data card. The data card has a pattern on its front surface formed from a light sensitive layer. The tablet device includes a housing, a card slot, a viewing aperture, an interface, a light source and a speaker. The card slot is arranged to receive the data card. The viewing aperture and the card slot are arranged such that the front face of the data card is visible through the viewing aperture when the data card is inserted into the card slot. The interface is 35 arranged to allow a user to interact with the tablet device. The light source is arranged to emit the pattern revealing light and illuminate the pattern on the data card. This causes the previously invisible pattern to emit colored light and become visible.

45 A particular embodiment of the above toy arrangement involves a data card whose front face shows various letters of an alphabet (e.g., C, Z, R, A, B and J) and a drawing (e.g., a drawing of car.) Each letter corresponds to a button on the tablet device. When the data card is inserted into the tablet device, the speaker of the tablet device asks the user to spell the object shown in the drawing. Once the user has pressed C-A-R in the correct sequence, the previously hidden letters are revealed and parts of the drawing are illuminated with a pattern revealing light. A previously unseen colored light is emitted from the drawing. A light show is performed to reward the user for choosing the correct letters. Other applications involve different data card designs that can help teach a child reading, spelling and other lessons.

Another embodiment of the present invention involves a 60 battle card game arrangement that includes game cards and a battle card platform. Each card includes an image formed from at least one light sensitive layer. The battle card platform includes a card engagement feature (e.g., slots) that are arranged to physically support two of the cards so that they are 65 visible to players of the game. The battle card platform also includes a light source that is arranged to emit a pattern revealing light towards one or both of the cards while they are

being held in position by the battle card platform. The image on the cards is generally invisible in the absence of the pattern revealing light but emits colored light and becomes visible when illuminated with the pattern revealing light.

One type of game that uses the battle card platform involves a player with a first card who wishes to attack or challenge a player with a second card. The first and second cards are inserted into the battle card platform. The player then interacts with the battle card platform (e.g., pushes a button on an interface) to initiate the attack. The battle card platform illuminates the first card with a pattern revealing light to create an attack animation. By way of example, there may be a drawing of a wizard with a magic staff on the first card. When the attack is initiated, the battle card platform illuminates a light sensitive layer on the first card that has the shape of a lightning bolt, which extends from the magic staff of the wizard. Because of the pattern revealing light, the previously invisible lightning bolt appears, flashes and emits colored light. This color display simulates the casting of lighting bolts by the wizard in battle. Furthermore, hits or damage done by each character can be tracked by illuminating other areas of a card to reveal simulated glowing wounds. The present invention contemplates using the platform with a wide variety of different games and cards.

BRIEF DESCRIPTION OF THE DRAWINGS

The invention and the advantages thereof, may best be understood by reference to the following description taken in conjunction with the accompanying drawings in which:

FIG. 1 is a flow chart of a method for illuminating and animating an image on a surface of an object according to a particular embodiment of the present invention.

FIG. 2 is a diagrammatic view of a toy arrangement involving a surface, a light source and a flame design according to a particular embodiment of the present invention.

FIG. 3A is a diagrammatic side view of the surface and flame design illustrated in FIG. 2.

FIG. 3B is an example graph that plots the volume of a sound against the intensity of colored light according to a particular embodiment of the present invention.

FIGS. 4A and 4B are diagrammatic views of an arrangement involving a face shape with an animated mouth region according to a particular embodiment of the present invention.

FIGS. 5A, 5B, 6A and 6B are diagrammatic perspective views of toy arrangements that involve a toy car according to various embodiments of the present invention.

FIGS. 6A-6B are diagrammatic perspective views of toy arrangements involving the use of conventional and pattern revealing lights according to a particular embodiment of the present invention.

FIGS. 7A-7B are diagrammatic top and side views of a tablet device according to a particular embodiment of the present invention.

FIG. 7C is a diagrammatic top view of a data card for use in a tablet device according to a particular embodiment of the present invention.

FIGS. 7D and 7F are diagrammatic top views of a tablet device with an inserted data card according to various embodiments of the present invention.

FIG. 7E is a diagrammatic cross-sectional view of the tablet device illustrated in FIG. 7D.

FIGS. 8A-8C are diagrammatic views of an arrangement involving game cards according to a particular embodiment of the present invention.

FIGS. 9A-9B are diagrammatic perspective and side views of a battle card platform according to a particular embodiment of the present invention.

FIGS. 9C-9F are diagrammatic views of game cards according to various embodiments of the present invention.

FIGS. 10A-10B are diagrammatic perspective views of toy arrangements involving a toy explorer figure and a toy magnifying glass according to various embodiments of the present invention.

FIGS. 11A-11B are diagrammatic perspective views of toy arrangements involving dolls according to various embodiments of the present invention.

In the drawings, like reference numerals are sometimes used to designate like structural elements. It should also be appreciated that the depictions in the figures are diagrammatic and not to scale.

DETAILED DESCRIPTION OF THE PREFERRED EMBODIMENTS

The present invention relates generally to the use of lighting effects in toys, games and educational devices. More specifically, various embodiments of the present invention involve directing a light towards a light sensitive layer. This light, when directed onto the light sensitive layer, reveals a previously hidden pattern on the layer. (Generally, such a light is referred to herein as a "pattern revealing light.") The pattern revealing light causes the light sensitive layer to emit visible, colored light. In various implementations, the light emitted is not necessarily confined to just one color, but rather a full spectrum of colors constructed from the primary colors of red, green, blue, and yellow. Different techniques such as additive color mixing and optical color mixing can be used to simulate even more colors. Preferably, the layer is difficult for a person to see or distinguish in the absence of the pattern revealing light (e.g., the layer is not a light sensitive layer with a highly visible color that is the same as that of its emitted light.) In various implementations, the pattern revealing light is used together with another colored light, flashed at a particular frequency or synchronized with sound to create richer, more dynamic light displays and to convey a sensation of animation and physical motion.

A wide variety of pattern revealing lights and light sensitive layers may be used. The pattern revealing light may be any suitable light that can trigger or cause the light sensitive layer to emit colored light. In various embodiments, for example, the pattern revealing light is a visible light, (nearly) invisible light, an ultraviolet light, an infrared light and/or another suitable type of light. The wavelength of the light may vary widely, depending on the needs of a particular application. In various implementations, for example, the wavelength of the pattern revealing light is less than 450 nm. A wavelength for the pattern revealing light of approximately between 400 nm and 420 or 430 nm works well for some applications, although higher and lower wavelengths may also be used. It has been determined that some of the above wavelengths can be useful for various toy applications in which it is desirable to have a strong emission of light from the light sensitive layer, as well as only a dimly visible or (nearly) invisible pattern revealing light. The light sensitive layers can be (nearly) transparent or generally invisible to the human eye before they are exposed to the pattern revealing light. The pattern revealing light can also be (nearly) invisible. Hence, by painting a surface of the toy with an invisible layer and shining an invisible light upon it, the illusion of a self-generated luminescence or glow can be created. By manipulating the layers and lights in various ways, simple

animated sequences, color change effects, and vibrant light displays can be generated. Such effects can be obtained even when the toy itself lacks an electrical system, batteries, a light bulb or a display screen.

Although the present invention contemplates a wide variety of light sensitive and light activated layers, particularly interesting effects can be obtained through the use of fluorescent layers. Fluorescent, light sensitive layers or paints do not merely reflect particular wavelengths of incoming light, as is the case with some other light activated paints. Instead, in various embodiments, the pattern revealing light excites atoms within the fluorescent layer. This causes the atoms to release photons that are visible in the form of a colored light. The intensity of the colored light can be controlled so that it changes in intensity or flickers at different frequencies. Additionally, the colored light can be mixed with other lights to generate dynamic, complex lighting effects. Although the glow from such layers is generally visible even in daylight, the glow is particularly striking in shaded or dark environments. Some of the toy arrangements and structure described in this patent application take advantage of this feature. Another advantage of various types of fluorescent layers is that the emission of colored light ceases or begins almost immediately after the exposure to the pattern revealing light ceases or begins. In comparison to various other methods that induce color change in an object through heat, water or chemicals, this approach can allow more control and a wider variety of possible light displays and/or animations.

Referring now to FIGS. 1 and 2, an example method 100 for using the pattern revealing light to create animated effects will be described. Initially, a toy arrangement 200 that includes a toy device 202, a speaker 204 and a light source 206 is provided (step 102 of FIG. 1.) A surface 208 of the toy device 202 is covered with one or more light sensitive layers 210. The light sensitive layer 210 is arranged to emit a colored light when exposed to the pattern revealing light 212.

The light sensitive layer 210 can be patterned and applied in any suitable manner. In the embodiment illustrated in FIG. 2, for example, the layer 210 is in the shape of a flame, but of course almost any shape is possible. Some implementations involve layers shaped in the form of a star, an insignia, a secret clue, a car headlight, a car engine, a magic spell, a discharge from a weapon, an explosion, fire, a lightning bolt, an attack action, a mouth on a face and a highlight in the hair of a doll. Layers may be applied to almost any kind of surface (e.g., rounded, flat, edged, etc.), material (e.g., plastic, metal, cloth, paper, wood, etc.) or structure (e.g., a card, a doll, a toy building, etc.) In some implementations, the layer is mixed or molded into plastic, or an object with such layers on its surface is embedded in clear or semi-transparent material.

Generally, the light sensitive layer 210 is invisible or barely visible until it is exposed to the pattern revealing light 212. Until then, it generally appears to match the color of any paint that it overlies. FIG. 3A is a diagrammatic side view of the toy device that shows how the light sensitive layer 210 can be layered over conventional paint 302. In the illustrated embodiment, conventional, non-light sensitive paint 302 covers the surface 208 of the toy device. The light sensitive layer 210 overlies the conventional paint 302. Generally, the light sensitive layer 210 is transparent or has the same color as the underlying conventional paint 302. Thus, in the absence of the pattern revealing light, the surface 208 appears to be covered only in paint of a single color. In some implementations, a blocking paint (not shown) may cover portions of the surface 208 or the conventional paint 302 that are not intended to emanate colored light or respond to the pattern revealing light. When struck by the pattern revealing light, conventional

paint can sometimes take on an undesirable hue. Blocking paint (e.g., a UV blocking pain in embodiments in which an ultraviolet light is used as the pattern revealing light) helps eliminate this hue and can render a more pure version of its intended color.

Afterward, at step 104 of FIG. 1, the light sensitive layer 210 is illuminated with a light source. The pattern revealing light 212 from the light source 206 is absorbed by the layer 210 and emits a colored light 214 in response. This colored light 214 may have a different color from that of the underlying conventional paint 302. In the illustrated embodiment, for example, the flame-shaped layer 210, which previously was white and therefore invisible against the underlying white paint 302, now emits the red, orange, and yellow light 214 and becomes much more visible.

Generally, the emitted colored light 214 is sufficiently strong such that it hides or obscures the color of the conventional paint 302 that underlies the light sensitive layer 210. Thus, in the above example, a person viewing the flame shape 10 would just see a blank whiteness prior to the use of the pattern revealing light 212, since the underlying paint 302 is white and the layer 210 is white or transparent. Once the pattern revealing light 212 is used, the person would see a red luminescent flame shape appear seemingly out of nowhere. The 20 flame shape therefore appears to change its color.

The appearance of the emitted light 214 can be controlled by adjusting the light source 206 or by using multiple light sources (step 106 of FIG. 1.) When the pattern revealing light 212 from the light source 206 flickers at a particular speed, the 30 emitted light 214 may flicker at the same speed. If the intensity of the pattern revealing light 212 is changed at a particular frequency, the intensity of the emitted light 214 can change at substantially the same frequency. This can be used to generate a variety of dynamic lighting effects. By way of example, in the illustrated embodiment, there are three light sources (not shown) that each direct pattern revealing lights towards different, contiguous portions of the same flame shape. Each light source changes the intensity of its pattern revealing light at different frequencies, which in turn causes the intensity of the colored light from each portion to change at different rates. Thus, the middle portion 216b flickers at a higher rate than the left portion 216a, which flickers at a higher rate than the right portion 216c. This makes the flame appear more realistic, since a real fire does not move uniformly and flickers in a somewhat random and unpredictable manner.

Multiple light sources can be arranged in a variety of ways, depending on the needs of a particular application. As discussed earlier, each light source 206 may be arranged to direct the pattern revealing light 212 towards a different region of an 50 object and/or a light sensitive layer. Accordingly, each region can be illuminated independently from the others. Various implementations involve light sources that arranged as a fixed, moving and/or motorized array of LEDs.

For some applications, it is also beneficial to use multiple 55 light sensitive layers that each emit differently colored lights. For example, in the illustrated embodiment, the middle portion 216b can be painted with a layer that emits a reddish color when it is exposed to the pattern revealing light. The left and right portions 216a/216c can be painted with different layers 60 that emit other colors, such as orange or yellow. To the human eye, the combination of flickering and different colors can create a more complex and realistic imitation of flame.

An interesting effect can also be achieved when the surface with the light sensitive layer 210 is in motion. In some 65 embodiments, a portion of or the entire toy device 202 is spun or moves along a circular path at high speed while being exposed to the pattern revealing light. The light sensitive layer

emits colored light in response to the exposure. Through a persistence of vision effect, the colored light and the motion of the object appear to form a three dimensional object.

A particular implementation of the above idea involves a ball that is painted with dots that are each formed from a light sensitive layer. While the ball is rolling, the spinning dots on the ball are illuminated with a strobing pattern revealing light. The dots formed from the light sensitive layer then each emit a colored light. By illuminating and rolling the ball in a particular manner, the ball can appear to be standing still or rolling in a reverse direction. This is because the eye only sees those moments when the ball is illuminated by the pattern revealing light and the light sensitive layer fluoresces.

The above displays can be further enhanced by synchronizing the colored light 214 with sound (step 108 of FIG. 1.) In the illustrated embodiment, for example, a speaker 204, which is coupled with the light source 206 and/or the toy device 202, generates a crackling, sizzling sound that approximates the sound of an actual fire. FIG. 3B is a simple example graph, in which curve 306 indicates the volume of the fire sound from the speaker 204 and curve 304 indicates the intensity of the colored light 214 from the layer 210. It is clear from the graph that the intensity 304 of the colored light 214 and the volume of the fire sound fluctuate in tandem with one another. That is, rises and falls in the intensity of the colored light 214 are matched by rises and falls in the volume of the sound. This also makes the flame act in a more realistic matter. Like a real fire, the crackling sound increases as the glow of the flame grows more intense but recedes when the glow of the flame gets weaker. A similar type of effect can be applied to a wide variety of patterns, structures and sounds. In a particular implementation, for example, the light sensitive layer 210 is applied to an exposed engine of a toy vehicle (e.g., toy engine 518 of toy car 502 of FIG. 5A.) As the colored light from the engine brightens or fades (e.g., as discussed above in connection with the flame shape), the volume of a revving engine sound may correspondingly increase or decrease.

In various embodiments, when the colored light 214 emitted from the layer 210 changes in some manner (e.g., frequency of flashing, intensity, etc.), an entirely new or different sound may be generated. A particular example involves a toy car with headlights that flash in tandem with the sound of a honking horn. In this simple example, when the headlights are not illuminated with the pattern revealing light (and thus do not glow), the speaker is silent or does not make the honking noise. When the headlights are illuminated with the pattern revealing light (and thus glow), the speaker generates a honking noise. This kind of synchronization resembles the operation of certain types of car alarms.

It should be appreciated that the aforementioned synchronization can be modified in a wide variety of ways. For example, it is not necessarily true that a greater intensity of colored light leads to a new sound or a louder existing sound. In some applications, a greater intensity of colored light may instead be correlated with a lower volume or no sound. Generally, the intensity of the colored light is varied to help support whatever animation effect is most appropriate for the sound.

The synchronization between the sound generated by the speaker 204 and the colored light 214 emitted from the layer 210 may be achieved in various ways. For example, the speaker 204 may be coupled with and/or communicate with the light source 206 (e.g., through a wire or cable, through a wireless data connection, using infrared light, etc.) In some embodiments, an algorithm (e.g., a pulse width modulation algorithm) is used to control and synchronize changes in the volume of the speaker 204 and changes in the intensity of the

pattern revealing light 212. Since the emission of colored light 214 is linked to its exposure to the pattern revealing light 212, the colored light 214 is also synchronized with the volume of the speaker 204. Alternatively, the speaker 204 may be coupled with a sensor (not shown) that detects the flashing, brightening and fading of the colored light 214 from the layer 210. The speaker 204 may be arranged to adjust its volume based on the data received from the sensor.

An advantage of using special layers and the pattern revealing light to produce animation and light displays is that the object emitting the colored light 214 (e.g., the object upon which a light sensitive layer 210 is painted, such as toy device 202) does not require an electrical system, batteries, light bulbs and/or a video display. In many toys that generate light displays and animation, this is not the case. Omitting such components can drastically reduce the weight and cost associated with the light-emitting objects and allow for very small objects (even smaller than a standard LED) to emit light.

It should be appreciated that the aforementioned methods and features can be used in a wide variety of different environments, structures, toys, games and educational tools. Any of the features described in connection with the aforementioned method (e.g., characteristics of the light sensitive layer 210, changes in the intensity of the colored light, synchronization with sound, etc.) may be applied to any embodiment described herein.

Referring next to FIGS. 4A and 4B, a toy arrangement 400 that includes a face shape 402, a light source 404 and a speaker 406 in accordance with a particular embodiment of the present invention will be described. The face shape 402 includes a mouth region 407 that is painted with a light sensitive layer 412. When the pattern revealing light 408 from the light source 404 is switched on or off, the face shape 402 can be animated to imitate the appearance of a talking person.

FIG. 4A is a view of the face shape 402 in the absence of the pattern revealing light. In this state, various facial features (e.g., mouth line, eyes, etc.) may be visible because they are painted using conventional colored paints and/or because they are defined by the shape of the toy surface. The light sensitive layer 412 is not visible, however. Hence, the color of the mouth region 407 is generally indistinguishable from the rest of the toy surface. Because only the mouth line is visible, the face shape imitates the appearance of a person who is keeping their lips closed and who is not talking.

FIG. 4B is a view of the face shape 402 when the light sensitive layer 412 at the mouth region 408 is exposed to the pattern revealing light 408 from the light source 404. The layer 412 at the mouth region now emits colored light in response to the pattern revealing light 408. In this example, the emitted light has a color that is substantially darker than that of the toy surface 410. As a result, the face shape 402 imitates the appearance of a person who is opening their mouth.

A speaker 406, which can be coupled with the face shape 402 and/or the light source 404, generates audible speech or words that are synchronized with the simulated opening and closing of the mouth. For example, in some embodiments, when a word of a sentence is being stated, the pattern revealing light 408 is turned on and the mouth region 407 emits a colored light. During gaps between words of a sentence in which nothing is said, the pattern revealing light 408 is turned off and the mouth region 407 is invisible against the toy surface 410. This gives an impression that the mouth region 407 is moving and uttering the words.

Referring next to FIGS. 5A and 5B, a toy arrangement 500 according to another embodiment of the present invention will be described. The toy arrangement includes a toy car 502,

a speaker 504 and a toy structure 506 that includes a light source 508 for emitting the pattern revealing light 510.

FIG. 5A is a diagrammatic perspective view of a toy car 502. The toy car 502 may have any suitable shape, composition or set of features. In this example, the toy car 502 includes a body 512, windows 514, wheels 516, an exposed front engine 518 and front headlights 520. All of these components may be painted in various colors using non-light sensitive, conventional paints. A light sensitive layer 524 covers the engine 518 and the headlights 520. For example, the engine 518 in this example is grey because of an application of grey paint on the engine 518, and over that paint there is also a transparent light sensitive layer 524. (Such layering was discussed in connection with FIG. 3A.) This layer 524 is generally invisible in the absence of the pattern revealing light.

FIG. 5B is a diagrammatic perspective view of the toy car 502 after it has been positioned within a toy structure 506. The toy structure 506 may resemble any kind of suitable structure, such as a garage, a house, a mountain, a tunnel, a building, a tent, etc. The toy structure 506 further includes an electrical system that powers a light source 508 for emitting a pattern revealing light 510. When the toy car 502 is positioned in the toy structure 506, the light sensitive layers 524 on the engine 518 and headlights 520 of the toy car 502 are exposed to the pattern revealing light 510 from the light source 508. As a result, colored light is emitted from the engine 518 and the headlights 520. The colored light has colors that may be different from the color of their underlying conventional paints (e.g., red for the engine, white or yellow for the headlights.) This gives an impression that the toy car 502 can self-generate light through the headlights 520 using an internal electrical system, when the toy car 502 in fact lacks any such system. Since the toy car 502 is shaded within the toy structure 506, the glow of the headlights 520 and the engine 518 are further accentuated and become particularly visible within the darkness of the interior of the toy building.

The speaker 504, which may be coupled with the toy building 506, the light source 508 and/or the toy car 502, generates engine or other suitable noises. As previously discussed, the flickering and intensity of the light emitted from the engine 518 may be synchronized with the tempo and/or volume of the sound from the speaker 504. For example, as the colored light emitted from the engine 518 gets brighter, the sound of a revving engine may grow louder. This simulates a situation in which an actual engine is being worked harder and generates correspondingly more noise. In another example, the colored light from the headlights 520 may be flashed in tandem with the intermittent beeping of a car horn. This gives the impression that the toy car 502 can self generate sound as well as light, especially since the sound is perfectly synchronized with the light.

There are various ways in which the above light and sound display can be initiated. In a particular embodiment, there is an interface coupled with the toy building. After a user places the toy car 502 in the toy building 506, the user can interact with the interface (e.g., by pressing a button, activating a switch, etc.) to cause the light source 508 to illuminate the toy car 502 and/or to cause the speaker 504 to emit synchronized sounds. In another embodiment, the activation of the light source 508 and/or the speaker automatically follows the placement of the toy car 502 in the toy building 506. For example, there may be a trigger (e.g., an optical sensor, a magnetic switch, a mechanical lever, etc.) in the toy building 506. By being placed in a particular position, the toy car 502 may be arranged to activate the trigger, which is coupled with the light source 508 and/or the speaker 504. In response to the activation of the trigger, the light source 508 and/or the

speaker 504 will also activate. It is also possible to use a sensor (RFID, bar code, etc) that would uniquely identify the toy car, causing a particular sequence of sound and light to occur which is specific to that type of toy car.

5 It is also possible to use standard colored lights in combination with pattern revealing lights to generate a multi-colored light display. FIGS. 6A and 6B are diagrammatic perspective views of a toy arrangement 600 involving a toy car 602 and two light sources 604a/604b. The first light source 604a is arranged to emit a colored, visible light 606. The second light source 604b is arranged to emit the pattern revealing light 608. When these light sources alternate in emitting light towards the toy car, the toy car 602 changes colors and glows in a particularly dynamic manner.

10 When the toy car 602 is not exposed to light from either light source 604a or 604b, it has the color(s) of any conventional, non-light sensitive paints that have been applied to its surface. Although light sensitive layers have been applied to the engine 610 and headlights 612 of the toy car 602, the layers are not generally visible in the absence of the pattern revealing light.

15 FIG. 6A is a drawing of the toy car 602 when the car is exposed to the colored light 606 from the first light source 604a but not from the second, pattern revealing light source 604b. The toy car 602 then tends to take on the color of the light 606 emitted from the first light source 604a. For example, if the first light source 604a is emitting a red-colored light, the entire toy car 602 may be bathed in a red hue. Since the colored light 606 from the first light source 604a is not specifically designed to trigger a reaction in the light sensitive layer, the light sensitive layer on the engine 610 and headlights 612 are not releasing photons and light at this time.

20 FIG. 6B is a drawing of the toy car 602 when the toy car 602 is exposed to the pattern revealing light 608 from the second light source 604b while the first light source 604a is turned off. In this situation, the engine 610 and the headlights 612, which are painted with the light sensitive layer, emit colored light that is the same or different from the color of any conventional paint that was also applied to those regions. The color of the emitted light may also be different from the color of the light produced by the light source 604a.

25 By moving between the three states described above (i.e., neither the first light source 604a nor the second light source 604b are turned on, only the first light source 604a is turned off, only the second light source 604b is turned on) each component of the toy car can flexibly shift between different colors and/or lighting effects. For example, the engine may have three different colors in the three states. When none of the light sources 604a/604b are turned on, the engine 610 has a color that is the same as that of the conventional paint that has been applied to it (e.g., grey.) In FIG. 6A, the engine 610 takes on a different hue that matches the color of the light generated by the first light source (e.g., red.) In FIG. 6B, the light sensitive paint on the engine emits photons to generate a color and/or glowing effect that is not visible in the other two states (e.g., an orange glow.)

30 Another way to add additional colors is to mix lights to create new colors. If the first and second light sources 604a/604b are turned on at the same time, the color of the light from the first light source 604a can mix with the color of the light emitted from the light sensitive layer on the engine 610 and headlights 612. Additive color mixing theory can be used to mix and generate any suitable range of light colors in this manner. For example, if the first light source 604a emits a blue light and the light sensitive layer on the headlights 612 is

11

arranged to emit a yellow light in response to the pattern revealing light 608, then the resulting glow from the headlights 612 will be white.

Referring next to FIGS. 7A-7F, a tablet device 700 according to another embodiment of the present invention will be described. The tablet device 700 includes a housing 702, a card slot 704 in the housing for inserting a data card, a viewing aperture 706, a speaker 708, a light source 710 for emitting the pattern revealing light, an electrical power source (e.g., one or more batteries), a processor and memory (not shown). The tablet device 700 is arranged to animate and illuminate patterns and drawings on the front face of a suitable data card using the pattern revealing light. As a child interacts with the tablet device 700, the tablet device 700 can thus respond to and reward particular actions to provide an improved educational experience for the child.

FIGS. 7A and 7B are diagrammatic top and side views of a tablet device according to a particular embodiment of the present invention. There is an interface 712 on the front surface of the tablet device 700. The interface 712 may include any number of buttons, switches, dials, etc. The front surface also includes a viewing aperture 706. A data card can be inserted into the tablet device 700 via the slot 704 in its side surface such that the front face of the data card is visible through the viewing aperture.

FIG. 7C is a diagrammatic top view of a data card 714, while FIG. 7D is a diagrammatic top view of the tablet device 700 when the data card 714 has been inserted into it. There are various symbols and patterns on the front face of the data card 714, such as letters, numbers, drawings, etc. In various embodiments, the data card also includes computer readable instructions that can be read by the tablet device 700. The instructions may help indicate how the tablet device 700 will respond to input from a user of the tablet device. In some embodiments, these instructions are visible in the form of a bar code on the outside of the data card 714. In another embodiment, the data card 714 includes a mechanical key that interfaces with and indicates the identity of the data card 714 to the tablet device 700.

The front face of the data card 714 may be designed in a wide variety of ways, depending on the needs of a particular application. In the illustrated embodiment, for example, the data card 714 is designed to help a child identify objects and count numbers. There are multiple items 716 drawn on the front face of the data card 714. Some of the items belong to a particular class of object (e.g., in this example, three of the items are insects) while the rest do not. There are also numbers 718 at the edges of the data card 714, which each correspond to and are aligned with a button 720 at the periphery of the viewing aperture.

In this example, the instructions on the data card 714 help the tablet device 700 to identify the data card 700 and formulate an appropriate question. Accordingly, the tablet device 700 asks the following question through the speaker: "How many insects are there?" If the child using the tablet device 700 presses the button corresponding to the correct number ("3"), then the tablet device 700 is arranged to reward this behavior by putting on a light show. In this example the animals appear in full color when illuminated by the pattern revealing light, as opposed to just black and white line drawings when not illuminated. If the child fails to press the correct button, the light source(s) may help reveal a correct answer to the child, provide a hint, etc.

The positioning of the pattern revealing light source 710 in the tablet device 700 is shown in FIG. 7E. FIG. 7E is a diagrammatic cross-sectional view of the tablet device 700 illustrated in FIG. 7D, as seen along plane X. The card 714,

12

after being inserted into the slot 704 of the tablet device 700, rests at the bottom of a recess 722 in the tablet device. One or more light sources for emitting the pattern revealing light are positioned at the sidewalls 724 of the recess 722 above the data card 714. The light source 710 is arranged to emit the pattern revealing light downwards toward the front face of the data card 714. As previously discussed, each light source 710 may direct light at different patterns or parts of the data card 714. As a result, different patterns (e.g., letters, drawings, etc.) may be illuminated independently from one another.

When the correct number of items is inputted by the user, the light source(s) turn on and emanate light towards portions of the front face of the data card 714 that are covered with a light sensitive layer. As a result, these portions will glow and emit colored light. In this example, when the correct answer of three insects is inputted, each of the three insect drawings is illuminated with the pattern revealing light from the light source(s) 710. The insect drawings may flash or glow in full color to indicate that a successful answer was provided. Alternatively, the insect drawings may be revealed sequentially instead of all at once. Additionally, music or sounds from the speaker 708 may be generated in tandem with the flickering of the emitted colored light. Such actions may be performed with any of the techniques and features discussed in connection with method 100 of FIG. 1. An audible message may be played from the speaker 708, telling the user that they chose correctly and did a good job.

FIG. 7F is a diagrammatic top view of a different data card 714 in a tablet device 700 according to another embodiment of the present invention. This data card 714 relates to a spelling game. Instead of numbers, there are various letters 726 from an alphabet that are arranged along the edges of the data card 714. After being inserted into the tablet device 700, each of the letters will align with and correspond to a button 720 on the tablet device. There is also a drawing 728 on the data card 714.

After the data card 714 is inserted into the tablet device 700, the tablet device is arranged to read the computer readable instructions on the data card 714. The instructions will cause the speaker 708 to audibly ask the user to spell what is shown in the drawing 728. In this example, the drawing 728 is of a car. The user must press buttons 720 in the correct order to spell C-A-R. Once this takes place, the tablet device 700 will respond again by using the pattern revealing light to animate a portion of the front face of the data card 714. For example, the car drawing 728 may be covered with a light sensitive layer. When the correct spelling is inputted by a child, the layer on the car drawing 728 may flash or flicker or explode in a glow of color as it is exposed to invisible pattern revealing light from the light source 710 in the tablet device 700. In another embodiment, a light sensitive layer is used to form the letters C, A and R, which each are illuminated independently by different light sources. As the user correctly chooses each letter in order, the corresponding letter will be illuminated one by one with the pattern revealing light and appear. Successfully picking all of the letters then results in an additional light show (e.g., the illumination of the layer on the car drawing 728.) This emission of colored light may be synchronized with suitable sounds from the speaker 708 (e.g., audible speech indicating that the user chose correctly, triumphant music, car sounds such as the revving of a car engine, etc.) Any of the approaches discussed in connection with FIGS. 1, 5A-5B and 6A-6B may be used to color and animate the car drawing on the data card.

Referring next to FIGS. 8A-8C, a card 800 for use in a card game according to another embodiment of the present invention will be described. The card 800 is a thin sheet of a suitable

material (e.g., paper, plastic, etc.) that includes a marking 802 that indicates how the card 800 is used during gameplay. There is also a pattern 804 on the card 800 that is formed from a light sensitive layer. This pattern 804, which generally has a secret impact on gameplay, is revealed when the card 800 is exposed to the pattern revealing light but is otherwise invisible.

An example of a card game will be described below. When the card game is played, a stack of cards are used by various players. The card illustrated in FIG. 8A is one of those cards. There are one or more other cards in the stack that, in the absence of the pattern revealing light, appear seemingly identical to the card 800 in the figure. However, the patterns 804 formed by their respective light sensitive layers may differ.

At a certain point in the card game, there is an opportunity to determine additional attributes of the card 800 that one of the players is holding. To make this determination, the player inserts the card 800 into a suitable light receptacle 806. FIG. 8B is a diagrammatic view of a light receptacle 806 according to a particular embodiment of the present invention. The light receptacle 806 is a container or structure with an opening for inserting the card 800. Inside the light receptacle 806 is a light source 808 for illuminating the card 800 with the pattern revealing light 810. In some implementations, the light receptacle 806 is partially closed and/or is arranged to at least partially shade the card 800 when it is inserted into the receptacle 806.

When the card is placed in the receptacle 806, the pattern revealing light 810 from the light source 808 is emitted onto the light sensitive layer on the card 800. This causes the pattern 804 formed by the light sensitive layer to glow. The pattern 804 provides additional information as to how the card can be played during the card game. It should be appreciated that two cards may appear identical in the absence of the pattern revealing light 810, but have different patterns 804 when exposed to the pattern revealing light. These different patterns 804 indicate that in some significant way, the two cards have a different, previously secret impact on gameplay.

The previously invisible pattern on the card can take a wide variety of forms. In the illustrated embodiment, for example, each card in the stack of cards has an array 812 of dots, dashes or marks. All of the cards in the stack have a seemingly identical array 812 of dots in the absence of the pattern revealing light. The dots may be painted onto the card using a conventional, non-light sensitive ink or paint. However, some of the dots in the array are covered with a light sensitive layer. The combination of dots that are covered in this manner may differ between different cards. When the card is exposed to the pattern revealing light 810, the covered dots glow, while the uncovered dots do not. In various embodiments, the pattern 804 of glowing dots may spell out a number or a word (e.g., the "S" on the card in FIG. 8C.)

This above concept of a card with hidden attributes can have an interesting impact on gameplay in a card game. Generally, in games where each player has their own hand, the player generally feels that they fully understand the cards that they were dealt with and their implications for the game. The above use of hidden patterns, however, adds another strategic dimension. That is, a player may know that he has a card of a particular type, but must also realize that he does not know the full value of the card until a particular point in gameplay during which the secret markings or patterns of the card can be revealed.

Referring next to FIGS. 9A-9B, a battle card game arrangement 800 according to a particular embodiment of the present invention will be described. The battle card game arrangement 800 includes a battle card game platform 802 that

includes a light source (not shown) for emitting a pattern revealing light and is arranged to hold at least two battle cards 804. The two cards 804 generally represent entities (e.g., monsters, weapons, magical spells, powers, allies, etc.) that are dueling or in conflict with one another. Generally, each of the two cards 804 is held by or represents a different player. The pattern revealing light and light sensitive layers on the cards may be used to enhance the card battles with animation and other effects.

FIGS. 9A and 9B are perspective and side views of an example battle card game platform 802. The battle card game platform 802 may be arranged in a wide variety of ways, depending on the needs of a particular application. In this embodiment, for example, the battle card game platform 802 includes a speaker 819 and vertical slits or insertion slots 806 for holding two cards (e.g., first card 814a and second card 814b) in place. Light sources are positioned on the battle card game platform 802 and are arranged to illuminate the cards with the pattern revealing light. The battle card game platform 802 may also include an electrical power source (e.g., one or more batteries) and an interface 808 (e.g., a button, switch, panel, etc.) for each player that is used to interact with the platform. In this example, a button can be pushed when a player having one of the cards wishes to initiate an attack against a player with a different card.

FIGS. 9C and 9D are enlarged views of the two cards. In this simple example, the first card 814a includes a drawing of a wizard and the second card 814b includes a drawing of a dragon. Of course, the battle cards 814a/814b may include any type of marking or drawing that helps indicate the significance of the card in gameplay. These designs or drawings are generally formed using conventional, non-light sensitive inks or paints and thus are visible in the absence of the pattern revealing light. As discussed below, each card includes a pattern painted in a light sensitive layer. However, as long as the cards are not exposed to the pattern revealing light, the patterns are generally invisible to the human eye.

After the cards 814a/814b are inserted into and held in place by the battle card game platform 802, one of the players initiates an attack with the first card 814a against the second card 814b, which is held by another player. This attack may be initiated by interacting with the interface 808 (e.g., by pressing the button.) When the button is pressed, the light source illuminates at least a portion of the first card 814a with the invisible pattern revealing light.

FIG. 9E shows the appearance of the first card 814a after it has been exposed to the pattern revealing light. The pattern revealing light reveals a previously unseen, glowing pattern 820a in the first card. In the illustrated embodiment, the glowing pattern 820a is in the form of a lightning bolt that is emitted from the wizard's hand on the first card 814a. In some embodiments, the defending player may then counterattack by using an interface 808 (e.g., pressing a button on the other side of the battle card game platform 802.) Accordingly, the invisible pattern revealing light is emitted towards the second card 814b, resulting in the appearance of another glowing pattern 820b (e.g., dragon breath from the dragon shown on the second card 814b.) This example effect is illustrated in FIG. 9F. As discussed earlier, the colored light that is emitted from the light sensitive layer on the cards may be made to flicker or change in intensity to make the animations more realistic and dynamic. The speaker 819 on the battle game platform may also play appropriate sounds (e.g., the crack of lightning, the rush of dragonbreath, etc.) and synchronize them with the flickering, brightening and fading of the colored light from the patterns 820a/820b.

The first and second cards **814a/814b** are not limited to one type of animation or colored light, but instead may support the generation of several, different types of light displays. Different regions of the card may be covered with a light sensitive layer and illuminated with different light sources. Thus, the different regions may emit colored light independently from one another. By way of example, the first card **814a** may have two distinct regions that are covered with two separate and different light sensitive layers. The battle card game platform **802** may have two light sources that are each arranged to illuminate and target a different region and layer. This allows the first card to have at least two types of patterns that may emit differently colored light at different times (e.g., a yellow lightning bolt for attacks by the wizard, a red streak to indicate that the wizard has been defeated, etc.) Additionally, the battle game platform may also include or more light sources that are arranged to emit visible, colored light. These light sources may be used to bathe portions of or an entire card with the color of the light. Such light can be used for color mixing together with a pattern revealing light source, as discussed previously, or be used alone to indicate that a particular stage of gameplay has been reached (e.g., an entire card may be bathed in a red color to indicate that the card has been defeated.)

Referring now to FIG. 10A, a toy arrangement **1000** according to a particular embodiment of the present invention will be described. The toy arrangement **1000** includes a toy explorer FIG. **1002a** and a toy environment **1004a**. The toy explorer FIG. **1002a** has a light source **1006** on its head that is arranged to illuminate a portion of the toy environment **1004** with a pattern revealing light. There is a pattern **1008a** on a surface of the toy environment **1004a** that is formed from a light sensitive layer.

The toy arrangement **1000** may be used by a child who wishes to simulate examining and exploring an unfamiliar environment. The toy explorer FIG. **1002a** may represent, for example, a soldier with infrared goggles who is searching through the darkness for clues or enemies. The light source **1006** may be positioned on or part of a pair of toy goggles, hat or headpiece that the toy explorer FIG. **1002a** is wearing. The toy environment **1004a** may be any structure that is arranged to imitate the physical environment around the explorer **1002a**. It may be painted or shaped to resemble, for example, various types of terrain, foliage, building structures, rocks, mountains, water, etc.

When the light source **1006** is not turned or when the pattern revealing light is aimed such that it is not illuminating the pattern **1008a**, the pattern **1008a** is generally invisible. When the child positions the toy explorer FIG. **1002a** in front of the toy environment **1004a** such that the pattern **1008a** is exposed to the pattern revealing light, the layer will become visible by emitting a colored light. The pattern **1008a** and the colored light can form any type of suitable shape. In this example, the toy environment **1004a** represents a forest and the colored light/pattern **1008a** has the form of a dangerous snake. This simulates a situation in which an explorer discovers hidden clues or enemies in his surroundings.

Referring now to FIG. 10B, a variation on the above toy arrangement **1000** according to another embodiment of the present invention will be described. The toy arrangement **1012** includes a toy magnifying glass **1002b** having a handle **1014** and a viewing element **1016**. The viewing element **1016** includes an aperture, possibly covered with a transparent material, and a light source **1006** suitable for emitting the pattern revealing light. The toy arrangement **1012** further includes a toy environment **1004b** that also contains a pattern **1008b** that is painted on a surface of the toy environment

1004b using a light sensitive layer. In the same manner as the toy explorer FIG. **1002a** illustrated in FIG. 9A, when the toy magnifying glass **1002b** is held in front of the toy environment **1004b** such that the pattern **1008b** on the toy environment **1004b** is exposed to the pattern revealing light, the previously invisible pattern **1008b** will glow and become visible. While playing the role of a detective, a child can use the magnifying glass to uncover previously secret clues (e.g., like the pattern **1008b**, which in this example represents a fingerprint, but could represent any suitable item, including a secret code, a silhouette, a trail, a marking, etc.)

Referring next to FIG. 11A, a toy arrangement **1100** according to another embodiment of the present invention will be described. The toy arrangement **1100** includes a doll **1102** and a light source **1104** arranged to emit a pattern revealing light **1108**. The light source **1104** may be coupled with the doll and/or be supported in any suitable structure (e.g., a lamp, a receptacle, etc.) The doll **1102** includes clothing with a pattern **1106** (e.g., a star on a circle) that is painted onto its surface with light sensitive layers. The pattern **1106** is generally invisible in the absence of the pattern revealing light. This can be because, for example, the clothing and the layers are the same color (e.g., if the clothing and layers are both white, one would be generally indistinguishable from the other.) Alternatively, it may be because the layers are transparent.

When the pattern **1106** is illuminated with the pattern revealing light **1108**, it becomes visible by emitting one or more colored lights. In the illustrated embodiment, the pattern **1106** includes shapes that appear to be superimposed over one another i.e., the pattern **1106** is made up of a star that is entirely surrounded by a circle. The circle and star patterns are contiguous and formed from two different types of light sensitive layers that are arranged to emit two different types of colored light. When UV light illuminates the pattern **1106**, the star portion emits a yellow light and the circle emits a blue light. The intensity of these colored lights can be changed in tandem with changes in the intensity of the pattern revealing light **1108**. For example, the colored lights can be made to flicker at increasing, decreasing or random frequencies. As previously discussed, these changes in intensity or frequency can be synchronized with sound from a speaker (not shown), which may be coupled with the doll **1102** and/or the light source **1104**.

A variation on the toy arrangement **1100** illustrated in FIG. 11A is shown in FIG. 11B. The toy arrangement **1120**, which also includes a pattern revealing light source **1124** and a doll **1122**, functions in a similar manner as the toy arrangement **1100** illustrated in FIG. 11A. A difference is that the doll **1122** has hair **1128** with highlight regions **1126**. The highlight regions **1126** are defined by and painted in a light sensitive layer. In some implementations, these highlight regions **1126** are formed by molding or mixing the light sensitive layer into the plastic that makes up the hair. These highlight regions **1126** behave like the pattern **1106** illustrated in FIG. 11A. That is, in the absence of the pattern revealing light, the highlight regions **1126** are generally invisible to the human eye and are indistinguishable from other parts of the hair **1128**. When the highlight regions **1126** are illuminated with the pattern revealing light from the light source **1124**, however, they emit a selected colored light and become visible. The light source may take the shape of a "magic brush" or other toy shape.

There are multiple references to a pattern revealing light and a light sensitive layer in this application. A pattern revealing light may be any suitable light that, when directed towards the light sensitive layer, causes the light sensitive layer to emit

a colored light. As previously noted, the pattern revealing light may be visible or (nearly) invisible, ultraviolet, infrared or any other suitable type of light. Generally, the light sensitive layer is specially formulated or arranged to react to the pattern revealing light and not to react or to react differently to other types of light. The exact manner in which the light triggers a light emitting reaction in the light sensitive layer may vary widely, depending on the needs of a particular application. In some embodiments, for example, the pattern revealing light excites atoms in the light sensitive layer. The excitation of the atoms causes the electrons of the atoms to change their quantum state and/or emit photons. The photons help form a colored light, which is emitted from the light sensitive layer in response to the pattern revealing light.

Although only a few embodiments of the invention have been described in detail, it should be appreciated that the invention may be implemented in many other forms without departing from the spirit or scope of the invention. Although particular techniques or features may be described in connection with a particular embodiment or drawing, it should be appreciated that any technique or feature from one embodiment may be applied to any other embodiment. For example, any of the aforementioned embodiments (e.g., the face illustrated in FIG. 4A, the toy car illustrated in FIG. 5A, the data card illustrated in FIG. 7C, the game card illustrated in FIG. 8A, the game card illustrated in FIG. 9C, etc.) may involve the use of light sensitive layers, patterns, sounds, techniques and light sources as described in connection with FIGS. 1 and 2 or any other figure. In the foregoing description, there are references to a pattern, marking or region that is invisible in the absence of a pattern revealing light. However, it should be appreciated that this should not be understood as requiring total and perfect invisibility. It may mean that the layer is transparent or has a color that is highly similar to or nearly identical to the color of a conventional paint that underlies and/or surrounds the layer. In some cases, of course, close examination of such an "invisible" layer may reveal its presence even without the pattern revealing light e.g., when the layer has a thickness that is small but noticeable if closely scrutinized. Additionally, the aforementioned embodiments generally are described as involving a fluorescent or light-emitting light sensitive layer and a pattern revealing light. However, the present invention also contemplates other types of layers (e.g., photochromic) that are not necessarily fluorescent, but that change color under ultraviolet or other types of activating light. By way of example, some implementations involve light sensitive layers or light activated layers that, instead of emitting light of a particular color, change colors through a chemical transformation of the layer in response to the activating light. In the foregoing description, there are some references to "ultraviolet light." In some embodiments, the ultraviolet light is entirely or nearly invisible to a human eye and/or is entirely or substantially entirely in the ultraviolet part of the electromagnetic spectrum. In still other embodiments, the wavelength of the ultraviolet light that is emitted by a light source is approximately between 360 and 430 nm, although various applications involve higher or lower wavelengths. The ultraviolet light is sometimes referred to herein as "invisible." This should not be understood as requiring perfect invisibility, but rather may mean almost or nearly invisible, rather than entirely invisible. Therefore, the present embodiments should be considered as illustrative and not restrictive and the invention is not limited to the details given herein, but may be modified within the scope and equivalents of the appended claims.

What is claimed is:

1. A method of illuminating a toy object with a pattern revealing light to create a colorful light display, the method comprising
  - 5 providing an object having at least one light sensitive layer that forms a pattern wherein the light sensitive layer is transparent such that the pattern is hidden from view in the absence of a pattern revealing light;
  - 10 illuminating the at least one light sensitive layer with the pattern revealing light using at least one light source, the pattern revealing light having a wavelength that is less than approximately 450 nm, the at least one light sensitive layer being arranged to absorb the pattern revealing light and emit a colored light in response such that the previously hidden pattern is revealed, wherein the at least one light sensitive layer, when not exposed to the pattern revealing light, is arranged to not emit the colored light;
  - 15 increasing and decreasing the intensity of the pattern revealing light repeatedly, thereby causing the intensity of the emitted colored light to also increase and decrease;
  - 20 generating sound at a speaker and synchronizing the sound with changes in the intensity of the emitted colored light; and
  - 25 using a control system that communicates with the speaker and the at least one light source to help synchronize the sound with the changes in the intensity of the emitted colored light.
2. A method as recited in claim 1 wherein:
  - 30 the pattern revealing light is generally invisible to a human eye; and
  - 35 the emitted colored light is not powered by an electrical system that is internal to the object.
3. A method as recited in claim 1 wherein:
  - 40 the at least one light sensitive layer includes a first light sensitive layer and a second light sensitive layer;
  - 45 the at least one light source includes a first light source that is arranged to emit a pattern revealing light at the first light sensitive layer and a second light source that is arranged to emit a pattern revealing light at the second light sensitive layer; and
  - 50 the method further comprises changing the intensity of the illumination from the first light source at a first frequency and changing the intensity of the illumination from the second light source at a different second frequency such that the colored light emitted from the first light sensitive layer flickers at a different frequency from that of the second light sensitive layer.
4. A method as recited in claim 1 wherein:
  - 55 the at least one light source includes a light source arranged to emit visible light and a pattern revealing light source arranged to emit the pattern revealing light;
  - 60 the method further comprises switching between different types of lights, which includes:
    - 65 illuminating the object with the visible light, the visible light having a first color, thereby bathing the object in the first color; and
    - 70 after the illuminating of the object with the visible light, turning off the visible light source to cease the bathing of the object in the first color and illuminating the object with the pattern revealing light from the pattern revealing light source, which causes the colored light to be emitted from the at least one light sensitive layer, the colored light having a second color that is different from the first color.

19

5. A method as recited in claim 1 wherein the object is a first card for playing in a card game, the method further comprising:

10 playing a card game involving a multiplicity of cards that includes the first card and a second card, the first and second cards having markings that indicate how the card is used in game play wherein the first and second cards appear generally identical when not exposed to the pattern revealing light, the first card having a first pattern formed from the at least one light sensitive layer that is different from a second pattern on the second card that is also formed from a light sensitive layer, the first and second patterns on the first and second cards being formed from transparent light sensitive layers such that the first and second patterns are hidden from view in the absence of the pattern revealing light; and

15 exposing the first pattern on the first card to the pattern revealing light, thereby causing the first pattern on the first card to emit the colored light, the colored light indicating a difference in how the first card and the second card can be played in the card game.

20 6. A method as recited in claim 1, the object being a first card for use in a battle card game, the method further comprising:

25 playing the battle card game in which the first card and a second card represent entities that are fighting with one another;

30 exposing the at least one light sensitive layer on the first card to the pattern revealing light, thereby causing the colored light to be emitted from a first pattern that is formed from the at least one light sensitive layer, the at least one light sensitive layer being generally invisible to a human eye prior to exposure to the pattern revealing light; and

35 animating an aspect of the fight between the first and second cards using the colored light from the first pattern.

40 7. A method as recited in claim 6 wherein the battle card game is played using a battle card game platform, the method further comprising:

45 inserting the first and second cards into a card engagement feature on the battle card game platform, the card engagement feature holding the first and second cards upright so that they are visible to players of the game; illuminating the first card that is being supported by the card engagement feature with the at least one light source, which is positioned on the battle card game platform; and

50 generating the sound at the speaker, which is positioned on the battle game card platform.

55 8. A method as recited in claim 1 wherein: the at least one light source includes a first light source arranged to emit a visible, colored light and a second light source arranged to emit a pattern revealing light; the first light source is arranged to emit a light of a first color and the at least one light sensitive layer is arranged to emit a light of a second color that is different from the first color when it is exposed to the pattern revealing light;

60 illuminating the at least one light sensitive layer with lights from both the first and second light sources; and mixing the first and second colors from the first light source and the at least one light sensitive layer to generate a light of a third color that is different from both the first and second colors, thereby causing the first light sensitive layer to emit a glow having the third color.

65 9. A method as recited in claim 1 wherein the object is moving rapidly such that the colored light emitted from the at

20

least one light sensitive layer on the object causes a persistence of vision effect, thereby creating an illusion of one selected from the group consisting of a three dimensional object and a two dimensional object with a shape that is different from said object.

10 10. A method as recited in claim 1 wherein: the object is in motion in a first direction; and the method further comprising:

turning on and off the pattern revealing light in rapid succession such that the colored light emitted from the at least one light sensitive layer causes an illusion of movement; and

varying the frequency of the turning on and off of the pattern revealing light to create an illusion of movement of the object in a second direction that is different from the first direction.

15 11. A method as recited in claim 1 wherein the object is a card having a drawing and a plurality of characters from an alphabet on a front face of the card and wherein the method further comprises:

receiving input from a user at a device; based on the input, determining at the device whether the user chose some of the characters in a correct sequence to spell a particular word that describes the drawing on the card; and

20 when the correct sequence has been inputted into the device, illuminating the at least one light sensitive layer on the card with the pattern revealing light, thereby causing the previously hidden pattern to become visible.

25 12. A method as recited in claim 1 wherein the object is a card, the at least one light sensitive layer forming the pattern on the card, there being a plurality of numbers and a plurality of items visible on a front face of the card, at least some but not all of the items belonging to a particular class of object and wherein the method further comprises:

receiving input from a user at a device; determining at the device whether the input indicates that the user correctly chose one of the numbers that represents how many of the items belong to the particular class of object; and

30 when the correct one of the numbers has been inputted into the device, illuminating the pattern on the card with the pattern revealing light, thereby causing the previously hidden pattern to become visible.

35 13. A method as recited in claim 1 wherein the object is a card, the method further comprising:

receiving the card at a viewing device such that a surface of the card forms a bottom of a recessed region in the device and is viewable through a viewing aperture on the device;

40 positioning the at least one light source on the device such that the at least one light source is arranged to direct the pattern revealing light onto the surface of the card;

45 receiving input from a user at the device; and in response to the input, activating the at least one light source to direct the pattern revealing light towards the light sensitive layer on the surface of the card, thereby revealing the previously hidden pattern.

50 14. A method as recited in claim 13 wherein: the at least one light source includes a first light source and a second light source that are positioned in different locations on the device and are arranged to illuminate different locations on the surface of the card; receiving input from the user at the device; and selectively activating the first light source or the second light source depending on the user input wherein the first

21

and second light sources are arranged to reveal different patterns on the card using the pattern revealing light.

15. A method as recited in claim **3** wherein: the first and second light sensitive layers are on a single surface of the object and are positioned adjacent to one another.

16. A method as recited in claim **1** wherein the pattern revealing light is at least one selected from the group consisting of: (1) ultraviolet light and (2) visible light.

17. A method as recited in claim **1** wherein the pattern revealing light has a wavelength between 360 and 430 nm.

18. A method as recited in claim **1** wherein the pattern revealing light has a wavelength between approximately 400 and 440 nm.

19. A method as recited in claim **1** wherein: the illumination of the at least one light sensitive layer with the pattern revealing light excites atoms in the at least one light sensitive layer such that electrons of the atoms emit photons which help form the colored light emitted by the at least one light sensitive layer.

20. A method of illuminating a toy object with a pattern revealing light to create a colorful light display, the method comprising:

providing an object having at least one light sensitive layer wherein there is a pattern painted on the object in the shape of a face, the face including a mouth region that is covered with the at least one light sensitive layer; illuminating the at least one light sensitive layer with a pattern revealing light using at least one light source, the pattern revealing light having a wavelength that is less

5

10

15

20

25

22

than approximately 450 nm, the at least one light sensitive layer being arranged to absorb the pattern revealing light and emit a colored light in response, wherein the at least one light sensitive layer, when not exposed to the pattern revealing light, is arranged to not emit the colored light;

increasing and decreasing the intensity of the pattern revealing light repeatedly, thereby causing the intensity of the emitted colored light to also increase and decrease to create an appearance of motion on the surface of the toy object;

generating sound at a speaker and synchronizing the sound with changes in the intensity of the emitted colored light; illuminating the mouth region with the pattern revealing light, thereby causing the mouth region to glow with the colored light and giving an impression that the mouth is opening;

not illuminating the mouth region with the pattern revealing light such that the at least one light sensitive layer in the mouth region does not emit the colored light, thereby giving an impression that the mouth is closed;

generating audible speech that is synchronized with the simulated opening and closing of the mouth, thereby giving impression that the mouth region is producing words; and

using a control system that communicates with the speaker and the at least one light source to help synchronize the sound with the changes in the intensity of the emitted colored light.
